(57) **CLAIM**

The ornamental design for a nasal pillow, as shown and described.

DESCRIPTION

FIG. 1 is a top perspective view of the nasal pillow of our design;

FIG. 2 is a bottom perspective view of the nasal pillow;

FIG. 3 is a front elevational view of the nasal pillow;

FIG. 4 is a rear elevational view of the nasal pillow;

FIG. 5 is a right side elevational view of the nasal pillow;

FIG. 6 is a left side elevational view of the nasal pillow;

FIG. 7 is a left side perspective view of the nasal pillow;

FIG. 8 is a rear perspective view of the nasal pillow;

FIG. 9 is a right side perspective view of the nasal pillow;

FIG. 10 is a front perspective view of the nasal pillow;

FIG. 11 is a right side perspective view of the nasal pillow and shown attached to headgear, a connector and a tube which are in broken line; and,

FIG. 12 is a right side perspective view of the nasal pillow and shown attached to headgear, a connector and a tube which are mounted on a user and are in broken line.

The broken lines in the drawings show environmental structure that form no part of the design to be patented.
